CLAIM

The ornamental design for a liquid oxygen connector, as shown and described.

DESCRIPTION

FIG. 1 is a front perspective view of an embodiment of a liquid oxygen connector according to our new design;

FIG. 2 is a front elevational view of the liquid oxygen connector shown in FIG. 1;

FIG. 3 is a rear elevational view of the liquid oxygen connector shown in FIG. 1;

FIG. 4 is a right side elevational view of the liquid oxygen connector shown in FIG. 1;

FIG. 5 is a left side elevational view of the liquid oxygen connector shown in FIG. 1;

FIG. 6 is a top plan view of the liquid oxygen connector shown in FIG. 1; and,

FIG. 7 is a bottom plan view of the liquid oxygen connector shown in FIG. 1.

The portions drawn in broken lines are shown for illustrative purposes only and form no part of the claimed design.
